(57) **CLAIM**

The ornamental design for neckwear to house and display metallic bars, as shown and described.

DESCRIPTION

FIG. 1 is a front view of a first embodiment of neckwear to house and display metallic bars showing my new design; FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front perspective view thereof;

FIG. 8 is a front view of a second embodiment of neckwear to house and display metallic bars showing my new design;

FIG. 9 is a rear view thereof;

FIG. 10 is a right side view thereof;

FIG. 11 is a left side view thereof;

FIG. 12 is a top view thereof;

FIG. 13 is a bottom view thereof;

FIG. 14 is a front perspective view thereof;

FIG. 15 is a front view of a third embodiment of neckwear to house and display metallic bars showing my new design;

FIG. 16 is a rear view thereof;

FIG. 17 is a right side view thereof;

FIG. 18 is a left side view thereof;

FIG. 19 is a top view thereof;

FIG. 20 is a bottom view thereof; and,

FIG. 21 is a front perspective view thereof.

The broken lines showing a neck strap represent environment which forms no part of the claimed design. The

(Continued)

remaining broke lines represent portions of the neckwear to house and display metallic bars which form no part of the claimed design.
